UNITED STATES PATENT OFFICE.

HOWARD L. AGEE AND SIDNEY A. AGEE, OF FORT WORTH, TEXAS.

SCREEN-HANGER.

1,324,768.

Specification of Letters Patent.

Patented Dec. 9, 1919.

Application filed May 20, 1919. Serial No. 298,477.

To all whom it may concern:

Be it known that we, HOWARD L. AGEE and SIDNEY A. AGEE, both citizens of the United States of America, residing at Fort 5 Worth, in the county of Tarrant and State of Texas, have invented certain new and useful Improvements in Screen-Hangers, of which the following is a specification.

Our invention relates to improvements in 10 screen hangers, and the object is to provide hangers for screens and other objects which will make the hanging of screens easily accomplished. One difficulty in tall buildings is the hanging of the screens. Our invention 15 provides hangers for screens which can be attached to the window frames from the inside of the buildings and to which the screens are easily adjusted from the inside of the building. Another object is that the 20 attachments assist in the adjustment of the screens to the window frames. Another object is that the screens may be released from the locking means and held suspended for the purpose of cleaning or adjusting the 25 window sash. Other objects and advantages will be fully explained in the following description and the invention will be more particularly pointed out in the claims.

Reference is had to the accompanying 30 drawings which form a part of this application.

Figure 1 is a front elevation of a window frame provided with a screen hung with the improved hangers. Fig. 2 is a vertical 35 section of the same. Fig. 3 is a side elevation of a window frame with the screen released from the locking devices and suspended in position to be readily hung, this being also the position of the screens after 40 they are hung and before they are locked in place. Fig. 4 is a perspective view of one of the hangers. Fig. 5 is an enlarged detailed view of one of the adjusting and suspending springs. Fig. 6 is a side elevation 45 of a hanger, showing a variation in the spring and a slight variation in the hanger.

Similar characters of reference are used to indicate the same parts throughout the several views.

50 The drawings show a window frame of ordinary construction. The screens are also of ordinary construction. The improved hangers 1 are attached to the window cap 2 by suitable screws 3. The screens 4' are 55 provided with eyes or hooks 5 and the hangers 1 have hooks 6. The suspending

and adjusting members consist of a spring 7 and two bent wires or rods 8 which may be duplicates in construction. The member 8 is adapted to engage the hook 6 and the member 9 is caught in the hook 4. Each member, 8 and 9, has hooks 10 which catch the spring 7 so that the spring is always held between the hooks 10 at the ends. From this construction it is seen that the 65 screen may be pressed downwardly on the compression of the springs. This method of the suspension of the screen is unlike the suspension of the screen in patent to Cornelison, No. 1,028,679, June 4, 1912. The 70 spring is easily suspended in position to be adjusted to the window frame. The hangers 1 are provided with keepers 11 which are set at an incline. To adjust the screen pull down on the screen until the top edge will 75 come under the keepers 11, and then release the pull on the screen. The keepers 11 will aid in pushing the screen close to the window cap as the springs 7 draw the screen up in place. It will be understood that the 80 hooks 10 at the bottom of member 8 serve as a spring seat for the spring. The keepers 11 hold the screen in place at the upper end. The screen is locked in place at the bottom by the pins or stops 12 and cam hooks 13. 85 The window sill 14 is beveled and the bottom of the screen is beveled so that when the hooks 13 are forced on the pins 12, the bottom of the screen is wedged against the window sill 14. It is practical to do this 90 because at the upper end of the screen, the screen will seal against the vertical portion of the window cap at 15 and it is not necessary that the top edge of the screen bear against the horizontal portion of the window cap above the screen. When the screen is suspended as in Fig. 3, the hooks 10 at the ends of the hangers 8 and 9 constitute 95 seats for the spring 7.

It is apparent that the screen can be released from the locked position, as shown in Figs. 1 and 2, and be held in such position as shown in Fig. 3 for cleaning or adjusting the window sash. Various changes in the construction and arrangement of the several parts may be made without departing from our invention. The keepers 11 may be curved more or less to bear against the outside of the upper part of the screen frame to clamp the same in place. The inner side 105 of the hanger may have a hook, but this may be simply an opening in the part 15' to re-

ceive a hook 16 of a spring 17 which is a variation from the spring 7 shown in Fig. 5.

What we claim, is,—

1. In combination with a window frame, 5 a hanger for mounting and adjusting screens comprising a bracket attached to the window cap and provided with a hook, expansible members caught in said hook at the upper end and attached at their lower 10 end to the screen, and springs mounted on said expansible members for retracting said members.

2. In combination with a window frame, 15 a hanger for mounting and adjusting screens comprising a bracket attached to the window cap and having a keeper for guiding and pressing the screen against the window cap and having a hook, expansible members consisting of rods each having a 20 loop at one end and a hook at the other end and a spring mounted on said members and supported in said hooks, the loop at the upper end of said expansible members being caught in the hook of said bracket and the 25 loop at the lower ends being attached to the screen.

3. In combination with a window frame, means for mounting and adjusting screens in the frame comprising a bracket attached

to the window frame cap and having a 30 keeper for guiding and pressing the screen against the cap and having a depending hook, expansible members consisting of a spiral spring and bent rods running through said spring and each forming a loop at one 35 end and terminating with hooks at the other end, said hooks forming seats for the spring, the loop at the upper end engaging the hook of said bracket and the loop at the lower end attached to the screen, and means 40 for locking said screen against the window sill.

4. In combination with a window frame means for guiding and adjusting and mounting a screen in the frame comprising 45 a bracket attached to the window cap and having a spring adjusting keeper formed with a bend for guiding and pressing the screen against the window cap and having a depending member for engaging a spring, 50 and a spring for engaging said depending member and attached to the screen for drawing the screen up into said bracket.

In testimony whereof, we set our hands, this 23rd day of April, 1918.

HOWARD L. AGEE.
SIDNEY A. AGEE.
